Technical drawing of a mechanical assembly, likely a conveyor or transport system, showing various components labeled with numbers 1 through 43. The drawing includes a top view of a frame with a grid of holes, a central horizontal beam, and various mechanical parts like gears, shafts, and supports. Labels are placed around the drawing, with some numbers appearing multiple times.

UNITED STATES PATENT OFFICE.

WALTER A. DORSEY, OF COLUMBUS, OHIO, ASSIGNOR TO THE BONNEY-FLOYD COMPANY, OF COLUMBUS, OHIO, A CORPORATION OF OHIO.

MINE CAR.

1,417,043.

Specification of Letters Patent. Patented May 23, 1922.

Application filed March 6, 1918, Serial No. 220,792. Renewed August 11, 1921. Serial No. 491,560.

To all whom it may concern:

- Be it known that I, WALTER A. DORSEY, a citizen of the United States, residing at Columbus, in the county of Franklin and State of Ohio, have invented certain new and useful Improvements in Mine Cars, of which the following is a specification, reference being had therein to the accompanying drawing.
10. The invention principally relates to the improvement of the frame members, body, wheel-carrying members and draft elements of mine cars, as more particularly herein-after set forth and claimed.
15. With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.
20. In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—
25. Fig. 1 is a side elevation of a mine car embodying the invention.
30. Fig. 2 is a bottom plan view of the same.
35. Fig. 3 is a top plan view showing the metal frame, wheel-carrying and draft elements separate from the body portions.
40. Figs. 4 and 5 are end elevations of the car frame and body.
45. Referring to the drawings, 1 indicates the wheels, ordinarily four in number, carried on the ends of axles 2 which pass through tubular bearings 3, which bearings are integral with a bottom body-supporting and 50 axle-carrying frame. This frame consists of two longitudinal side members 4 and cross members 5, which together with the bearing sleeves 3 are ordinarily cast in one piece.
55. 6 is a draft element or draw-bar which extends from end to end of the car approximately at the level of the floor thereof and formed at each end at 7 with holes for coupling pins 8. The draw-bar is bolted at 9 to the cross-bars 5, said bolts preferably passing through the central flooring board 10. The draw-bar is also bolted at 11 to bottom transverse bars 12 of the end frames, the end frames also having upwardly extending side members 13, outwardly extending members 14 and upper vertical side members 15. These side portions of the end frame are attached to the bottom bars 12 by vertical tenons 16 which pass down through openings 17 in said bars 12 and are held in place by pins 18, or equivalent means, engaging under the bottom bar. By this construction a knock-down mine car is or may be provided which can be easily transported and assembled at will.
60. Each end frame is of angle formation, the bottom bars 12 being formed with horizontal flanges 19 which extend inward under the bottom boards, and with vertical flanges 20 which strengthen the bottom bars for pulling and buffing strains. The upper members of the end frame are formed with longitudinal flanges 21 against which the outer surfaces of the side boards engage and with vertical flanges 22 against which the ends of said boards fit. The end boards are secured in place to the flanges 22 by bolts 23. The bottom bars 12 are projected outward to form buffing and coupling elements and are vertically perforated to correspond with the coupling pin holes 7. In addition to the 65 bolts 9, the wheel frame is provided with bolts 24 which secure the bottom boards of the body to the top of the wheel frame.
70. At about the middle of the wheel frame there are provided center posts 25 to which 75 the side boards are secured, these center posts having depending tenons 26 which pass down through openings 27 in the wheel frame and are held in place by pins 28.
75. With the wheel frame may be combined one or more cast metal brackets 29, of angle form, which brace against the wheel frame and are secured to the bottom of the body by bolts 30, the central bolts preferably passing through the draw-bar 6, so that hauling 80 strains may be directly applied to the wheel frame independently of the bottom body-elements of the car.

The middle center posts 25 have attached thereto at one side of the car vertical guide rods 31 on which works vertically a brake block 32 formed to be applied to the upper 5 and inner sides of the wheels. This brake block is operated by an angle arm 33 pivotally mounted at 34 on the wheel frame by means of cast lugs 35, said arm being pivoted at 36 to an arm 37 depending from the 10 brake block. The upper end of the arm 33 has pivoted thereto at 38 a link 39, said link being operable by a hand lever 40 pivoted at 41 to the car body and extending up through a slot 42 to the interior of the latter at one 15 side of the same. Strengthening plates 43 are preferably applied to the side boards at the top of the same at points between the end frames and the center posts 25, said plates having pivotally bolted thereto at 44 20 the ends of a yoke bar 45 which extends transversely across and is attached to the top of the end gate or dumping door 56 (Fig. 4). This door is further supported by an inclined yoke bar 46 which extends 25 transversely across the middle or lower part of the door at the outer side of the same and the ends of which extend longitudinally of the car and are bolted to the bar 45 at 47. This pivotal mounting of the door 56 is pref- 30 erably connected with the side posts 25 by diagonal braces 48 which are bolted to the plates 43 at 44 and are bolted to the side frames or center posts at 49. On the front face of the door is also applied a vertical 35 strengthening and door-actuating bar 50 which is secured by bolts 51 to the door-boards and to the transverse portion of the bar 45, and to the transverse portion of the bar 46; and I may also apply vertical 40 strengthening members of similar character, as shown at 52 and 53 in Fig. 4. At the rear end of the car (Fig. 5) these bracing members may be omitted, but in that case a trans- 45 verse bar 54 is combined with and bolted to the end frame and end board at or about the top of the latter.

The door-actuating bar 50 is formed with a hook 57 by means of which the door may be swung upon the pivots 44 to dump the car, 50 or by which the door may be held up while the front end of the car is tilted down.

The bottom or buffer bars are or may be cast with an upwardly extending coupling element 55 having an end opening for the 55 coupling link and vertically perforated for the pin 8.

There is thus produced a mine car frame and body of very strong construction and which may be very economically built and 60 repaired, and the strains of hauling and buffing are so transmitted that they do not deteriorate the weaker and ordinarily wooden parts of the car body. The car is thus made capable of withstanding the severe usage in- 65 cident to the haulage of coal in and from

mines, and the metal portion of the car is minimized, and is also practically inde- structible.

Among other advantages of making the wheel frame independent of the end frames, 70 which construction is permitted by the use of the central through draw-bar, is the result that, without change of most of the metal parts, cars may be varied in longitudinal dimensions as may be required, either 75 when they are being built or when they are being repaired.

What is claimed is:

1. In a coal mine car, in combination: a knock-down metal frame adapted for the 80 reception of wooden or other body members, and comprising a wheel frame formed with side bars and cross bars and having integral therewith bearing sleeves for the wheel axles, and frames independent of said wheel frame 85 and comprising bottom buffing and drafting members and formed with seats and side members removably attached to the said bottom members in said seats, and a central hauling and buffing member attached to the 90 said wheel frame and provided at its ends with means whereby the coupling devices may be connected therewith.

2. In a coal mine car, in combination: a knock-down metal frame adapted for the 95 reception of wooden or other body members, and comprising a wheel frame formed with side bars and cross bars and having integral therewith bearing sleeves for the wheel axles, end frames independent of said wheel frame 100 and comprising bottom buffing and drafting members and side members removably attached to the said bottom members, center posts removably attached to said wheel frame, and a central hauling and buffing 105 member attached to the said wheel frame and provided at its ends with means whereby the coupling devices may be separably connected therewith, and with said end frame. 110

3. In a coal mine car, in combination: a metal frame adapted for the reception of wooden or other body members, and comprising a wheel frame formed with side bars and cross bars and having integral therewith 115 bearing sleeves for the wheel axles, end frames independent of said wheel frame and comprising bottom buffing and drafting members and side members removably attached to the said bottom members, a central hauling and buffing draw bar attached to the said wheel frame and provided at its ends with means whereby the coupling devices may be connected therewith and with said end frames, and a haulage bracket attached to 120 said draw bar and bearing against the rear side of said wheel frame.

4. In a coal mine car, in combination: a metal frame adapted for the reception of wooden or other body members, and com- 125

- prising a wheel frame formed with side bars and cross bars and having integral therewith bearing sleeves for the wheel axles and formed with vertical sockets, end frames 5 comprising bottom buffing and drafting members formed with vertical sockets and side members having tenons passing down through the sockets of said bottom members and formed with longitudinal and trans- 10 verse flanges, and a central hauling and buffing member attached to the said wheel frame and provided at its ends with means whereby the coupling devices may be connected therewith.
- 15 5. In a knock-down mine car, in combination: a bottom central frame having axle bearings; end frames comprising side mem- bers and bottom bars having inwardly and upwardly extending flanges and outwardly 20 extending coupling elements which are rigid with said bottom bars; and a continuous draw bar separably united with said bottom bars and adapted to be united with said coupling elements by the draft-coupling 25 pins, said bottom bars being provided with seats for the separable connection of the lower ends of said side members.
6. In a knock-down mine car, in combination: a bottom central frame having axle 30 bearings; end frames comprising side mem- bers and bottom bars having inwardly and upwardly extending flanges and outwardly 35 extending coupling elements which are rigid with said bottom bars; and a continuous draw bar separably united with said bottom bars and adapted to be united with said
- coupling elements by the draft-coupling pins.
7. In a coal mine car, in combination: a wheel frame, a body attached to said wheel frame and having an open end, a dumping door arranged in said open end, transversely extending yoke bars attached to the said door and having rearwardly extending ends at the outer sides of the car body and converging to a point of pivoting, means whereby said ends are pivoted to the car body, means for swinging said door and yoke bars upward relative to the car body for dumping, center posts at the sides of the car body and attached to the wheel frame, and links at the sides of the body and connecting the said pivot means with the said center posts. 45
8. In a knock-down mine car, in combination: a bottom central horizontal cast metal frame having axle bearings; end frames comprising cast metal bottom bars and side members separable therefrom; middle side members separably connected with said bottom frame; and longitudinal bottom and 50 side boards extending from end frame to end frame separable from and adapted to be attached to all of said frames to connect the otherwise independent bottom frame and 55 end frames.
- 65 In testimony whereof, I affix my signature, in presence of two witnesses.

WALTER A. DORSEY.
